poration of New Jersey

Application July 2, 1936, Serial No. 88,680
In Great Britain July 19, 1935

15 Claims. (Cl. 101—96)

This invention relates to marking machines and is herein illustrated as embodied in a machine of the type disclosed in an application for Letters Patent of the United States Serial No. 48,961, filed on November 9, 1935, in the name of H. E. Elliott.

In order to make a mark comprising a double row of characters by the use of a marking head of no greater width than has been necessary heretofore to make a single row of characters, the marking head, as disclosed in the above-mentioned application, has been provided with pairs of disks, each pair having an aggregate width equal substantially to the width of one character, and each disk having type-carrying projections extending from its periphery and arranged to overlap the periphery of the other disk so that when the disks are in assembled relation the projections on one are in peripheral alignment with those on the other. In the above-mentioned machine, a series of pairs of marking disks and the disks of each pair are yieldingly held together in assembled relation by means including a spring against the resistance of which, when one disk of any pair is to be reset, the other of that pair is separated from that being reset, in order to permit their type-carrying projections to pass each other, by the interaction of cams formed on the inner surfaces of the disks of each pair.

One object of the present invention is to facilitate the resetting of a marking disk in a machine of the type referred to above by relieving the above-mentioned cams of the necessity of opposing a spring pressure when separating the marking disks. To this end, the invention provides, in connection with a series of rotatably mounted marking disks, means comprising an actuator for selectively rotating the disks to reset them and yielding means for normally holding the marking disks together, and means for relieving the yielding pressure between the marking disks when one is to be reset. In the illustrated machine, the means for relieving the yielding pressure between the marking disks is operated by mechanism actuated by movement of the actuator into engagement with a marking disk to be reset, which actuator subsequently is swung peripherally of the disk to reset the disk by rotating it through the angle between successive type-carrying projections on the disk.

During the resetting of the right-hand disk of any pair, for example, in a machine of the type in question, those disks at the left of it are displaced laterally to permit the type-bearing pro-

jections of the adjacent left-hand disk to be passed without interference by the disk being reset; but the disk being reset and all those to the right of it are positively locked against movement to the right. Similarly, when a left-hand disk of any pair is to be reset, those disks to the left of it are locked against displacement to the left but those to the right of the disk to be reset are displaced laterally. In view of the foregoing and in order to prevent disassembling of the displaced marking disks when one is reset, it is another object of the invention to control those disks which are displaced laterally with respect to the others when one disk is reset, whereby any possibility of the disks becoming disassembled or turned or any interference to the resetting of the selected disk is avoided.

Pursuant to this object, another feature of the invention comprises means operated by the above-mentioned second movement of the actuator to permit displacement of those marking disks opposite to the disk being reset at substantially the same rate and to the same extent as the camming action between those disks of that pair one of which is being reset, whereby the group of disks which are displaced laterally with respect to the others will be held together in intimate contact throughout the resetting operation although the yielding pressure normally existing between them is relieved. This feature of the invention insures that the marking disks, notwithstanding their separation at one locality, will be held in intimate contact with each other elsewhere although the yielding pressure between them which normally holds them together is relieved, as mentioned above, throughout the resetting operation.

The above-mentioned selective locking of the disks against displacement toward one side or the other of the marking head during a disk resetting operation and the positive locking of the marking disks against any lateral displacement during a marking operation is effected by locking means controlled by a control member having a limited swinging movement and carrying plates one of which, when the control member is swung to either side of a neutral position, unlocks the marking disks at one side of the head, the disks at the opposite side of the head being locked.

In order to insure against unintended starting of the machine as by accidental treading, the invention contemplates the provision of safety devices which prevent the treading of the machine under certain circumstances, such as before the operation of resetting a marking disk is completed or so long as a guard disposed in

front of the marking head is raised to permit access to the head.

To this end, the illustrated machine includes stop mechanism operated by either the above-mentioned control member or the guard for preventing the movement of the treadle-operated means by which a marking operation is initiated whenever the control member is moved away from its neutral position or the guard is moved 10 away from its operative position.

The setting of the marking disks is preserved by a series of locking members or pawls, one pawl being provided for each pair of disks and each pawl being adapted to enter a gap between and 15 to engage adjacent type-bearing projections of its corresponding pair of disks. That pawl corresponding to a disk being reset is retracted from the disk during the resetting operation; but upon its completion the pawl is released and moves 20 into its operative position under yielding pressure. If, owing to the resetting operation being incompletely, the pawl is not released or if, even though released, the pawl is prevented from moving into its operative position on account of interference with a projection of a marking disk, treadling of the machine is prevented by means, 25 constituting another feature of the invention, actuated by any pawl when retracted and cooperating with the previously mentioned control member, for preventing movement of the control member into its neutral position. Thus, the possibility of making a mark the characters of which are misaligned is prevented because the control member cannot be moved to its neutral position 30 to permit the machine to be treadled unless all of the projections of the marking disks are in alinement with each other and the above-mentioned pawls are in their operative positions.

It is customary, in the operation of marking 40 machines employing a web impregnated with ink or carrying another form of marking substance, to move the web once for each marking operation in order to present a fresh portion of the web to the action of the marking head for each 45 marking operation. Another object of the present invention is to minimize the likelihood of strain or breakage in the web owing to the usual abruptness of its feed movement. Invention is therefore to be recognized in the provision of a 50 work support, a marking head movable toward and away from the support to mark a work-piece thereon, a web carrying a marking medium, and interrelated means for operating the marking head and drawing the web from its 55 source of supply in two stages per cycle of the marking head. In the illustrated machine, the means for drawing the web is operated once just before the marking operation and again immediately after the marking operation and before 60 the end of the cycle. Accordingly, the required amount of feed may be imparted to the marking web at substantially less speed and hence with less strain than if a single actuation of the web per cycle of the marking head were relied 65 upon to provide the required feed movement.

These and other features of the invention will appear more fully from the following detailed description and will be pointed out in the appended claims.

Fig. 21 is a plan view of an auxiliary marking member illustrated in Fig. 14; and

Fig. 22 is a view in perspective of a pair of 45 marking disks.

The illustrated machine comprises a marking head 10 (Figs. 1 and 2) of the type disclosed in application Serial No. 48,961, filed November 9, 1935, in the name of H. E. Elliott, the marking head 10 being mounted for movement toward and away from a work support to mark a work-piece placed thereon, it being understood that the present invention contemplates the use of either a horizontally reciprocating work support 12 or a 50 relatively fixed work support 14 (Fig. 12). Any of the well-known methods of marking may be carried out in the use of the usual machine; that is, impressions may be made merely by bringing the marking head 10 when heated into engagement 55 with the work directly, or the marking head 10, heated or not, may press a web 16 (Fig. 3) against the work, the web being impregnated with ink or carrying a metallic marking substance or other suitable marking medium. The 60 marking head 10, as herein illustrated, is moved toward and away from the work support substantially vertically with a parallel motion and to this end is mounted on a carrier 18 (Fig. 2) pivoted at its lower end to a lever 20 which is 65 fixed on a shaft 22 mounted for oscillation in the machine frame 24. The carrier 18 is pivotally connected at its upper end by means of a hollow shaft 26 to a link 28 mounted to swing on a stud 30 fixed in the frame 24. The lengths of the 70

lever 20 and link 28 between the points where they are connected to the carrier 18 in the frame 24 are equal; and the heightwise distance between the shafts 22 and 30 is equal to that between the shaft 26 and the pivotal connection between the carrier 18 and the lever 20. Thus, the marking head 10 is mounted to move with a parallel motion and is operated by connections comprising a lever 32 rotatably mounted on the shaft 30 and having an arm 34 pivoted at 36 to an eccentric strap 38 driven by an eccentric 40 on a drive shaft 42. An upwardly extending arm 44 of the said lever is arranged to engage a plunger 46 mounted to slide in a recess 47 the upper part of the link 28 in which recess is housed a spring 48 the tension of which may be adjusted by a nut 50 threaded in the recess 47. The spring 48, acting through the lever 32, normally holds a shoulder 52 on the lever 32 against a similar shoulder 54 on the link 28. Thus the marking head 10 will be positively raised from the work support but may be held against the work support with an adjustable yielding pressure and with an adjustable dwell during the period when the shoulders 52, 54 are separated owing to the provision of the yielding connection afforded by the spring 48 between the bell crank 32 and the link 28, the adjustment in each instance being facilitated by the nut 50.

30 The drive shaft 42 is driven from a countershaft 56 having a pinion 58 which meshes with a gear 60 fixed to the drive shaft 42. The countershaft 56 is driven from a belt-driven pulley 62 rotatably mounted on the shaft 56 through a clutch mechanism of the type disclosed in Letters Patent of the United States No. 1,124,620 granted January 12, 1915, upon the application of A. E. Jerram. In the stopped position of the machine a member 64 (Figs. 3 and 6) of the illustrated clutch mechanism, which corresponds to the member 134 of the structure disclosed in the above-mentioned Jerram patent, engages a shoulder on an arm 66 of a bell crank lever 68 pivoted at 70 to a casing 72 of the clutch. When the machine is to be started the arm 66 is moved downwardly out of engagement with the member 64, thereby allowing the latter to swing to the right (Fig. 3) and permitting the clutch to close under the action of springs to effect a driving connection between the pulley 62 and the countershaft 56. The arm 66 is thus drawn downwardly by a treadle-operated rod 74 which is pivoted at 75 to the lower end of a latch 76 having a hooked end 78 which is urged toward the end of the arm 66 by a spring 80 connecting the latch 76 and the bell crank 68. The latch 76 and rod 74 are also pivoted at 75 to an arm 82 of a bell crank lever pivoted at 84 to the machine frame 24 and having another arm 86 adapted to engage a rod 88 mounted to slide in the frame 24, as will be explained later, to prevent the machine from being treadled at certain times when the machine might be damaged if operated under power. When the treadle rod 74 is lowered against the resistance of a spring 90 which tends to hold the latch 78 in its position illustrated in Figs. 3 and 6 and the machine is started, a depending arm 92 of the bell crank 68 is swung to the left and an arm 94 (Figs. 2 and 3) fixed to the shaft 22 moves upwardly beside the lower end of the arm 92 and prevents the arm 66 from rising under the influence of the spring 80 until the drive shaft 42 has made substantially a complete revolution, during which time the countershaft 56 makes three revolutions owing to a 3 to 1 ratio between

the diameters of the gear 60 and the pinion 58. Toward the end of the revolution of the drive shaft 42 the arm 94 is swung downwardly and releases the arm 92 of the bell crank 68, thereby permitting the arm 66 to re-engage the member 64, which oscillates from right to left (Fig. 3) during each revolution of the countershaft 56, and hence to disengage the clutch.

The rod 88 is mounted to slide in a fixed bearing 96 into the path of the arm 86 so as to prevent the clutch from being tripped and may be thus operated as a safety measure in connection with a guard 98 (Figs. 1 and 2) normally positioned close to the work support 12 in front of the marking head 10 so that the operator's fingers cannot possibly be injured by the marking head during the operation of the machine. The guard 98 comprises a glass plate 99 mounted between arms 100 which are pivoted to the frame 24 at 102 to permit the guard to be raised so as to provide access to the marking head. When the guard is so raised, by means to be described below, the rod 88 is moved into the path of the arm 86, thereby to prevent the machine from being treadled so long as the guard is in its raised position. To this end, the lower end of a lever 104 (Fig. 2) integral with one of the arms 100 is pivoted at 106 to a link 108 having a slotted end adapted to receive a pin 110 extending from the upper end of a lever 112 pivoted at 114 on the machine frame 24. The lower end of the lever 112 is bifurcated to receive a pin 116 fixed in the forward end of the rod 88. A spring 118 normally urges the rod 88 forwardly of the machine and yieldingly holds the pin 110 at the rearward end of the slot in the link 108. The guard 98 may be held in its raised or lowered position by means of a latch 120 carried by the upper end of the lever 104 and adapted to enter any of a series of slots 122 in a plate 124 fixed to the upper part of the machine frame. It will now be apparent that as the guard 98 is raised the link 108 is moved forwardly and causes the lever 112 to move the rod 88 against the pressure of the spring 118 into the path of the arm 86 (Figs. 3 and 6) positively to prevent the treadle rod 74 from being lowered and the clutch from being tripped.

Further insurance against misoperation of the machine is afforded by the provision of means for preventing the machine from being accidentally started as the result of lowering the guard 98 if at that time the operator should unintentionally be pressing on the treadle of the machine. To this end the rod 88 has on one side a wedge surface 126 (Fig. 6) which, as the rod is moved rearwardly, as for example when the guard 98 is raised, swings downwardly an arm 128 rotatably mounted on the shaft 84. The arm 128 is connected by a link 130 to the latch 76 so that when the arm 128 is moved downwardly the latch is moved away from the arm 66 whereby the latter is prevented from being moved to trip the member 64 if the latch 76 were to be lowered. The arm 128 has pivoted thereto a pawl 132 from which extends an arm 134, the latter being connected by a spring 136 to the latch 76 whereby the pawl 132 is yieldingly held against the outer surface of the bearing 96. During rearward movement of the rod 88 its wedge surface 126 causes the arm 128 and pawl 132 to be moved downward until the latter engages a shoulder 138 on the bearing 96 thereby causing the latch 76 to be held by the link 130 in inoperative position. If subsequently the rod 88 is moved for-

wardly as the result, for example, of lowering the guide 98 and also if the operator at this time is pressing on the treadle, even though the arm 82 may be moved downwardly as soon as the rod 88 has been moved out of the path of the arm 86, the clutch will not be tripped because the latch 76 is held out of engagement with the arm 66 by the link 130. However, continued downward movement of the arm 82 will cause a pin 140 on the latch 76 to engage the arm 134 and unlatch the pawl 132 thereby permitting the spring 66 to hold the latch 76 against the arm 66 so that not until after the treadle has been fully raised again after being accidentally operated will its depression cause the clutch to be tripped.

The illustrative machine may be provided with the relatively fixed work support 14 (Fig. 12) or the sliding work support 12 (Figs. 1 and 8 to 11, inclusive) which moves from a position in front 20 of the marking head rearwardly to carry a work-piece beneath the marking head.

The work support 14 includes a fiber block 142 yieldingly supported by a rubber cushioning pad 144 which allows the block 142 to yield slightly under the pressure of the marking head 10. The support 14 has a depending stem 146 which is slidably mounted in a sleeve 148. The sleeve 148 is slidably mounted in the machine frame 24 and may be adjusted vertically to adjust the 30 height of the support 14 by turning a nut 150 threaded on its upper end and resting on the machine frame. The nut 150 is prevented from rising by a key 152 secured to the machine frame and rotation of the sleeve 148 is prevented by a key 154 received in a slot in the machine frame and a groove 156 in the sleeve 148. The sleeve may be clamped in adjusted position by a screw 158 which passes through a split portion of the frame and through the key 154.

If the fingers or hand of the operator become 40 jammed between the marking head 10 and the work or for any other reason the machine is stalled, the support may be quickly lowered without loss of its heightwise adjustment. For this purpose a pair of toggle links 160, 162, the opposite ends of which are seated in blocks in the sleeve 148 and stem 146, are pivoted at their adjacent ends to a bar 164 which may be moved rearwardly to collapse the toggle 160, 162. The bar 164 is pivoted at 166 to an arm 168 secured 50 on a shaft 170 rotatably mounted in the machine frame. The shaft 170 also has secured on it a crank 172 by which the shaft 170 may be rotated. When the crank 172 is swung upwardly from its position shown in Fig. 12, the bar 164 is drawn rearwardly, the toggle is broken rearwardly, and the support 14 is quickly lowered. Such movement of the crank is limited by the engagement of a stop face 174 on the crank 60 with a pin 176 fixed to the machine frame. When the table is in its operative position as shown in Fig. 12, the toggle 160, 162 is broken slightly forwardly and marking pressure on the table holds the forward end of the bar 164 against the inside of the sleeve whereby the table is prevented from moving downwardly.

The reciprocating work support 12 has secured to it a fiber block 178 (Fig. 8) which is yieldingly supported against the pressure of the marking head 10 by a rubber pad 180. The work support 12 is carried by a slide 182 which is slidably mounted in a guide way 184 formed at the head of a downwardly extending stem 186 which may be mounted in the machine in place of the 75 above-mentioned sleeve 148. Heightwise adjust-

ment of the support 12 is effected by turning the nut 150 which is adapted to receive the stem 186. The stem 186 has a keyway which receives the plate 154 to prevent rotation of the stem and it may be clamped in adjusted position by the 5 screw 158. The slide 182 is reciprocated to carry a work-piece from a position in front of the guard 98 to another directly beneath the marking head by a link 188 (Fig. 1) which at one end is pivoted to the rear end of the slide and its other end 10 is connected to a lever 190 pivoted at 192 to the machine frame. The lever 190 has pivotally connected to it a link 194 which is pivotally connected to a cam lever 196 mounted to swing on a stud 198 secured in the machine frame. The cam lever 196 has on it a cam roll 200 received in a cam groove 202 in a cam 204 secured to the shaft 42. The cam groove 202 is so shaped that during each rotation of the shaft 42 the work-support 12 is moved rearwardly to carry a work-piece beneath the marking head 10 before the head descends and then forwardly after the work-piece has been marked.

The work-piece is clamped to the support 12 as it moves rearwardly by a pair of bars 206, 206 (Figs. 9 and 10) which press the work-piece at each side of the marking head against inclined faces 208, 208 on the support 12 so that the work-piece is firmly gripped on the support and at each side of the marking head is pressed below the upper face of the support 12 and is thus prevented from being damaged by the web 16 if that is inked or by any parts of the machine as the marking head descends. The bars 206, 206 extend forwardly from brackets 210, 210 which are 30 slidably mounted on studs 212, 212 secured to the support 12 and are pressed downwardly by springs 214, 214 which are adjustable by means of nuts 216, 216 threaded in the brackets 210, 210. The brackets 210, 210 have extending from them 40 bifurcated lugs 218, 218 adapted to receive pins 220, 220 extending from H-shaped arms 222, 222 (Fig. 8) pivoted to extensions 224, 224 from a plate 226 secured to the support 12. The pins 220, 220 have rotatably mounted thereon cam 45 rolls 228, 228 arranged to engage cams 230, 230 formed on a bar 232 fixed to the support 12. As the support 12 moves rearwardly the cam rolls 228, 228 travel down the cams 230, 230 and allow the springs 214, 214 to press the bars 206, 206 50 against the work-piece; and as the support 12 moves forwardly the cam rolls 228, 228 travel up the cams 230, 230 and raise the bars 206, 206 so that the marked work-piece can be removed and a fresh work-piece can be placed on the support 12. 55

The provision of a reciprocating support of the type described above on which a work-piece is clamped and which carries the work-piece beneath the marking head 10 tends to minimize 60 the risk of the operator's hands being inadvertently trapped between the marking head and the work-piece or between other parts of the machine and the support since there is no necessity for the operator's hands to approach these 65 parts. The guard 98, which is preferably provided when either form of work support illustrated herein is used, and the devices hereinbefore described whereby under certain conditions the machine is prevented from being operated, also tend to prevent injury to the operator. 70

To assist in properly positioning a work-piece on the support 12 two pins 233, 233 project above the upper surface of the support, one at each 75

side of the plate 226, these pins being adapted to be engaged by the forward edge of the work-piece. The pins 233, 233 extend upwardly from the rear ends of bars 234, 234 slidably mounted beneath the upper surface of the support 12. The bars 234, 234 have slots 235 through which pass screws 236, 236 (Fig. 8) which hold the bars up against the lower side of the support but permit the bars to be adjusted lengthwise to vary the position of the pins 233, 233. The bars 234, 234 have depending forward ends 238, 238 to facilitate their adjustment.

The web 16 which may be impregnated with ink or carry a metallic marking substance or other suitable marking medium is wound in a supply roll indicated at 240 (Fig. 3) and is pressed against the work-piece by the marking head 10 to impress the desired mark on the work-piece. The roll 240 is mounted on a spindle 242 rotatably mounted in a bracket 244 which is secured to the right-hand side of the carrier 18. The roll 240 is held between a flange 246 (Fig. 2) which is adjustable along the spindle 242 by means of a nut 248 threaded on the spindle and another flange 250 which is locked in position by a pawl 252 which engages ratchet teeth (not shown) on the spindle. The roll 240 is thus clamped between the flanges 246, 250 and may be positioned on the spindle 242 so that the web 16 passes directly beneath the marking head 10 by adjustment of the flanges 246, 250 along the spindle. Rotation of the spindle 242 is resisted frictionally in order to keep the web 16 taut by means comprising a collar 253 which is keyed to the spindle 35 and is pressed against the bracket 244 by a spring 254 engaging the collar and also engaging a nut 256 threaded on the spindle 242. The spring 254 also causes a collar 258 fixed to the spindle 242 to press against the bracket 244.

The web 16 is led from the supply roll 240 about guide rolls 260, 262 rotatably mounted on the bracket 244 close to the carrier 18, thence under the marking head 10 and later between a feed roll 264 and a presser roll 266 (Figs. 3 and 5). The feed roll 264 is secured on the forward end of a shaft 268 (Fig. 5) which is rotatably mounted in a casing 270 fixed to the carrier 18, the shaft having secured on its rear end a pinion 272. The presser roll 266 is rotatably mounted on a stud 274 in a carrier 275 swinging from an arm 276 which is integral with the casing 270. This carrier 275 is urged by a spring 278 to cause the presser roll 266 to hold the web against the feed roll 264. The pinion 272 is driven by a gear 280 secured on a shaft 282 which is rotatably mounted in the casing 270.

In order to minimize the feeding strain on the web 16, the feed roll 264 is operated in two separate steps but at a lower speed than would be possible if only one feed movement of the web per impression of the marking head were made. In the illustrative machine the feed roll 264 is operated once to bring a fresh portion of the web 16 under the marking head 10 immediately after it has been raised from the work and again just before the next impression is made by mechanism comprising a ratchet wheel 284 the teeth of which are engaged by two pawls 286, 288 (Fig. 4) which are pressed against the ratchet teeth by springs (not shown). The pawls 286, 288 are pivoted on arms 290, 292 respectively which are independently pivoted on the shaft 282 and the arms are pivoted to the lower ends of links 294, 296 the upper ends of which are pivotally connected to a shaft 298 mounted to rock

in a lever 300 pivoted at 302 (Fig. 1) to the casing 270. The lever 300 is oscillated by a link 304 which is connected to an arm 306 pivoted at 308 to the machine frame 24. The arm 306 has pivoted to it one end of a rod 310 the other end of which is pivotally connected to a lever 312. The lever 312 is pivotally connected at 314 to a cam arm 316 pivoted at 318 to the machine frame. The cam arm 316 is oscillated by connections comprising a cam roll 320 on the arm 316 and adapted to run in a cam groove 322 in a cam 324 secured on the shaft 42. In order to vary the feeding movement of the web 16, the lever 312 is provided with an adjustable fulcrum block 326 adapted to be held in any desired position of adjustment in an arcuate guideway 328 in the lever 312. To this end, the block 326 is pivotally mounted on one end of an arm 330 of a bell crank lever which is pivoted at 332 to the machine frame; and the other arm 334 of the bell crank lever carries a clamp bolt 336 passing through an arcuate slot 338 in a bracket 340 secured to the machine frame whereby the fulcrum block 326 may be held in any desired position in the guideway 328. As the cam arm 316 is swung by its cam 322 forwardly and rearwardly during a single rotation of the shaft 42 the lever 312 is rocked on the pivot of the block 326 and through the rods 310, 304 swings the lever 300 first rearwardly and then forwardly. The swinging of the lever 300 first raises the links 294, 296 (Fig. 4) and causes the pawl 288 to rotate the ratchet wheel 284 in a counter-clockwise direction, and then lowers the links and causes the pawl 286 to rotate the ratchet wheel in the same direction. Each of these rotations of the ratchet wheel 284 causes the web 16 to be fed, and the cam groove 322 is so formed that one movement of the ratchet wheel and web occurs not only while the marking head 10 is being moved down but also when it is being moved up, as stated above. The cam groove 322 is so formed that the feeding movement of the web is interrupted while the marking head is making an impression on the work. The distance through which the web 16 is fed during each of its feeding movements is controlled by moving the bell crank lever 330, 334 to adjust the position of the fulcrum block 326 with respect to the guideway 328 in the lever 312.

In order to prevent the web feeding mechanism from being operated owing to relative movement between the carrier 18 and the machine frame 24, the link 304 is made the same length as and parallel to a line between the centers of the shafts 26 and 30 (Fig. 2).

When the paper has passed between the feed roll 264 and the presser roll 266 it is wound up by a spindle 342 (Fig. 5) rotatably mounted in the casing 270. The spindle 342 has on its forward end flanges 344, 346 and adjusting means, similar to the flanges 246 and 250 and their adjusting means as described above. The spindle 342 is rotated by a frictional overdrive comprising a pinion 348 rotatably mounted on the spindle and connected to the gear 280 by an idler pinion 350 rotatably mounted on a screw 352 secured in the casing 270. The pinion 348 is pressed against a flange 354 on the spindle by a spring 356 confined between a collar 358 keyed on the spindle and a nut 360 threaded on the spindle so that the spindle is frictionally driven. The pinion 348 is driven at a speed somewhat faster than that of the shaft 268 to

insure that the web will not accumulate between the feed roll 264 and the spindle 342.

The marking head 10 comprises a plurality of pairs of marking disks 362 (Fig. 22), of the type disclosed in the above-mentioned application, rotatably mounted on a hollow shaft 364 supported at its ends by brackets 366, 366 (Fig. 19) which are fixed to arms 368, 368 formed integral with the carrier 18. The hollow portion of the shaft 364 is adapted to receive an electric heating unit (not shown) for heating the disks 362 the temperature of which is indicated to the operator by a gage 370 (Fig. 1). When one of the disks 362 is rotated to change the setting of its marking characters, all of the disks at one side of that being moved are moved axially of the shaft 364 to permit the type-carrying projections 369 on that disk being reset to pass those on the other disk 362 of the same pair, and after the disks have been reset they are clamped together to prevent any axial movement. Such lateral clamping of the disks 362 is effected by rings 372 one of which is slidably mounted on the shaft 364 at each side of the disks 362, each ring having projecting laterally from it three pins 374 arranged to slide in the brackets 366 and connected at their ends by a three-armed member 376. The members 376 are engaged at their centers by the forward ends of levers 378 pivoted at 390 to the arms 368, the rear ends of the levers 378 being urged apart by a spring 382 which surrounds telescoping rods 384 which pass freely through the ends of the levers 378 but have lock nuts 386 threaded thereon and adapted to transmit the yielding pressure of the spring 382 to the levers 378. Thus, the effect of the spring 382 is normally to cause the rings 372 to hold the marking disks 362 close together. Further, the disks 362 are positively held against each other during the marking operation by means of stop plates 388, 390 fixed to a control shaft 392 rotatably mounted in the carrier 18, the plates being adapted to engage the ends of rods 394 mounted to slide in the carrier 18 and being pivotally connected at 396 to the rearmost ends of the levers 378.

Moreover, it is to be understood that in the illustrated machine, as in the case of that disclosed in the above-mentioned application to which reference may be made for a complete description of the marking disks 362, the separation of the disks 362 of that pair of which one disk is being reset is effected by the interaction of cams 379 extending from their inner surfaces, and that when the right-hand disk is reset by being rotated all of the disks to the left of it are moved axially of the shaft 364. Similarly, when the left-hand disk 362 of any pair is reset, all of the disks to the right of the disk being reset are moved to the right axially of the shaft 364. In order to permit this movement of the disks one or the other of the rings 372 is permitted to move axially of the shaft 364 when one of the marking disks is to be reset.

To this end, the control shaft 392 is adapted to be rotated in opposite directions from a neutral position, in which it is illustrated in Fig. 15, to remove one or the other of the stop plates 388, 390 from engagement with the co-operating rods 394. A segmental gear 398 (Figs. 2 and 14) fixed to the shaft 392 is arranged to mesh with another segmental gear 400 fixed to a shaft 402 mounted to rotate within the shaft 26 by which the carrier 18 is mounted on one of its supporting links, the gear 400 being provided opposite to its

toothed portion with spaced shoulders 404 adapted to co-operate with a pin 406 fixed in the carrier 18 to limit the movement of the gear 400 and hence the shaft 392. Upon swinging a crank 408 fixed to the shaft 402 in a clockwise direction (as when a left-hand marking disk 362 of any pair is to be reset) until one of the shoulders 404 abuts the pin 406, the shaft 392 is rotated in a counterclockwise direction and causes the plate 390 (Fig. 15) to be swung downwardly away from the end of the adjacent rod 394 so as to permit the right-hand lever 378 (Fig. 3) to swing away from the marking disks 362, thereby permitting the right-hand ring 372 to move to the right; and, similarly, if it is desired to reset the right marking disk of any pair, the crank 408 is swung to the limit of its movement in a counterclockwise direction, thereby to cause the plate 388 to be swung upwardly away from the end of the adjacent rod 394, and hence to permit the left-hand lever 378 to release the left-hand ring 372 and also the marking disks 362 to the left of the disk which is to be reset.

Insurance against accidental treading of the machine while the marking disks 362 are being reset is provided by mechanism including a link 410 (Fig. 2) pivoted at 412 to one side of the gear 398 and having its other end slotted to receive the pin 110 on the lever 112. It will now be apparent that when the crank 408 is swung toward either side of its neutral position preparatory to resetting a marking disk the link 410 will be moved forwardly and will cause the rod 88 to be moved rearwardly to control or prevent the tripping of the clutch in the same manner as described above in respect to the movement of the guard 98.

When it is desired to change the setting of the right-hand disk of a pair of marking disks 362, the crank 408 is first swung to the limit of its movement in a counterclockwise direction and then a crank 414 is rotated in a clockwise direction one revolution for each step between successive projections 369 on the marking disk when it is desired to move the marking disk. The crank 414 is fixed to a shaft 416 rotatably mounted in a yoke 418 (Fig. 15) having depending arms pivoted at 420 to the sides of the carrier 18 concentrically with the shaft 364 which carries the marking disks 362. The yoke 418 is oscillated when the crank 414 is rotated by a cam 422 (Fig. 14) adapted to engage the sides of a forked member 424 fixed to the carrier 18. The movement of the yoke 418 is transmitted to the selected marking disk 362 to be reset by one of a series of actuators 426 which are pivotally mounted on a shaft 428 extending between the arms of the yoke 418, the actuators being disposed in heightwise alignment with the adjacent pair of marking disks 362 and each actuator having a tooth 430 adapted to enter a gap 432 between adjacent projections 369 of its corresponding pair of disks. All of the actuators 426 except that corresponding to the selected marking disk to be reset are yieldingly held in an inoperative position, that indicated in dotted lines in Fig. 15, by leaf springs 434 bearing against the tails of the actuators and clamped against the base of a control bracket 436 (Fig. 16) mounted to swing about the shaft 428. The inoperative position of the actuators 426 is determined by their engagement with a shaft 438 which is threaded in the control bracket 436 and has a single tooth 446 which is moved from one actuator 426 to the next as the shaft 438 is rotated through one revolution by a crank 512 75

and which, when in its lowermost position, holds the selected actuator below the others just above the adjacent gap 432. The bracket 436 comprises a forked member 442 between the sides of which is disposed a cam 444 fixed in the shaft 416 which is rotated when the crank 414 is turned. Accordingly, when the right-hand disk 362 of any pair is to be reset and the crank 414 is rotated in a clockwise direction (Fig. 14), the selected actuator 426 (Fig. 15) is first swung into the gap 432 by the operation of the cam 444, whereupon the cam 422 causes the yoke 418 to swing forwardly of the machine and to move the selected marking disk through the angle between successive projections 369. Before the reverse movement of the yoke 418 begins the cam 444 will have caused the tooth 430 on the selected actuator 426 to be removed from the gap 432 so that upon a rearward movement of the yoke 418 the actuators 426 move idly out of engagement with the marking disks.

If a left-hand disk 362 is to be reset, the yoke 418 is first swung by the cam 422 to the extreme of its forward movement before the selected actuator 426 is moved into the gap 432, whereupon the cam 444 swings the bracket 436 about the shaft 428 to move the tooth 430 of the selected actuator 426 into the gap 432. During the rearward movement of the yoke 418 the selected actuator 426 first rotates the left-hand marking disk being reset through the angle between successive projections on the marking disk and then is moved out of the engagement with the marking disk.

As stated above, the marking disks 362 are normally pressed together by the spring 382. In order to minimize the wear on the cams (not shown) on the marking disks which effect their separation when a disk is to be reset and also to minimize frictional resistance to the resetting of the marking disks, means are provided in the illustrated machine for relieving the pressure of the disks against each other throughout the resetting operation. This means includes a wedge-shaped cam 448 (Figs. 13 and 15) secured to an extension 450 of the bracket 436. At each side of the cam 448 and slidably mounted on a rod 452 connecting the sides of the yoke 418 are sleeves 454 the adjacent ends of which are adapted to be engaged by opposite sides of the cam 448. Each of the sleeves 454 has mounted thereon a roll 456 which, when the control bracket 436 is swung to move the cam 448 rearwardly of the machine, is moved into engagement with arcuate cams 458 (Figs. 13 and 14) mounted on levers 460 arranged to pivot about horizontal axes on studs 462 fixed in the carrier 18. Each lever 460 has a depending arm 464 which is pivotally connected to one of the above-mentioned rods 384 (Fig. 19).

When the shaft 416 is rotated in a clockwise direction as seen in Fig. 14 to reset the right-hand one of a pair of disks 362, the bracket 436 is, as hereinbefore described, first swung in a direction to bring a tooth 430 of a selected one of the actuators 426 into the gap 432 before the yoke 418 moves forwardly. During this movement of the bracket 436 the cam 448 is swung rearwardly and moves the sleeves 454, 454 outwardly along the rod 452. As a result of this movement of the sleeves their rolls 456, 456 engage the cams 458, 458 and move the lever arms 464, 464 and hence the rods 384 inwardly, causing the nuts 386 to be moved away from the clamping levers 378 and the spring 382 to be compressed, thus relieving the pressure between the disks 362. When the

shaft 416 is to be rotated to reset a right-hand marking disk the plates 388, 388 will have been moved, as described above, into such a position that the right-hand locking lever 378 is prevented by the plate 390 from moving so as to 5 prevent its associated ring 372 from moving outwardly and the left-hand locking lever 378 is free to move to permit lateral movement of the disks to the left of the disk to be rotated. The left-hand cam 458, as will be seen in Figs. 3 and 13, 10 is recessed rearwardly of an inclined portion indicated at 466 so that when its roll 456 is moved outwardly it moves the left-hand lever 460 only enough to move the left-hand nuts 386 away from the left-hand clamping lever 378. The shape of 15 the right-hand cam 458, as will be seen in Fig. 13, is such that when its roll 456 is moved outwardly it moves the right-hand lever 460 so far that the right-hand nuts 386 move inwardly a distance which is sufficient to allow the forward end 20 of the arm 378 to swing freely outwardly, when it is allowed to do so, a distance which is a little greater than the width of the projections on the disks 362. The disks 362 are therefore, on the commencement of the rotation of the shaft 416 25 in a clockwise direction, relieved from the action of the spring 382 by the inward movement of the left-hand nut 386, but, since the right-hand clamping lever 378 is positively held against movement by the plate 390, the disks cannot move to the right along the shaft 364; and since the left-hand nuts 386 have been moved only a small distance away from the left-hand clamping lever 378 the disks can, prior to the forward swinging movement of the frame 418, move only slightly 30 on the shaft 364 toward the left. The disks 362 can therefore at this time separate only very slightly along the shaft 364 and any such separation will not be sufficient to allow either of the disks at opposite sides of the disk with which 35 the tooth 430 on the selected actuator 426 is in engagement from moving along the shaft 364 into engagement with the tooth 430, and hence preventing forward movement of the actuator frame 137 since, as will hereinafter appear, all 40 of the disks except that to be reset are prevented from rotating at this time.

When the yoke 418 is moved forwardly by rotation of the shaft 416, the left-hand cam roll 456 engages the inclined face 466 on the left-hand cam 458 and, just as the disk 362 being reset commences to separate from the adjacent disk under the influence of their cams, moves the arm 464 of the left-hand lever 460 inwardly and moves the left-hand nuts 386 farther away from the left-hand clamping lever 378 a distance which just allows the aforesaid disks to separate freely without their cams having to compress the spring 382. At the end of the forward movement of the yoke 418 the tooth 430 is as hereinbefore described, moved out of engagement with the marking disk 362 just reset and at the same time the cam 448 is moved forwardly, permitting the left-hand levers 460 to swing inwardly, permitting the spring 382 to expand and, through the left-hand clamping lever 378, to clamp the disks 362 together again.

As the yoke 418 approaches the end of its forward movement and before the tooth 430 is removed from the gap 432, the right-hand roll 456 travels along an inclined face 468 on the right-hand cam 458 and allows the right-hand nuts 386 to be moved by the spring 382 nearly into engagement with the right-hand clamping lever 378. 75

It is to be understood, however, that, since the right-hand rod 394 is held against axial movement by the plate 390 when the yoke 418 is swung forwardly to rotate a right-hand disk 362, the action of the right-hand cam 458 during this movement plays no part in controlling lateral movement of the disks. When the yoke 418 is swung rearwardly during the latter part of its oscillation to rotate a left-hand disk, however, the right-hand rod 394 will be free to move axially, as will hereinafter appear, and the left-hand rod 394 will be held against axial movement by the plate 388 so that the right-hand cam 458 then replaces the left-hand cam 458 in controlling lateral movement of the disks.

When it is desired to reset the left-hand one of a pair of disks 362, the shaft 392 is rotated by swinging the crank 408 forwardly to remove the plate 390 from engagement with the right-hand rod 394 so that the right-hand lever 378 is free to move and the left-hand clamping lever 378 is prevented from moving by contact of the left-hand rod 394 with the plate 388. The shaft 416 in this case is rotated in a counterclockwise direction and at the end of the forward movement of the bracket 436 the tooth 430 is moved into the appropriate gap 432 by the cam 444. At the same time the wedge-shaped cam 448 is moved rearwardly and the right-hand nuts 386 are moved slightly away from the right-hand clamping lever 378 when the right-hand roll 456 engages the recessed portion of the right-hand cam 458. The disks are now relieved from side-wise pressure by the spring 382 and, as the actuator frame 418 moves rearwardly to rotate the selected disk 362, the right-hand roll 456 moves along the inclined face 468 and, just as the disk being reset is separated from its adjacent disk, moves the right-hand nuts 386 farther from the right-hand lever 378 so that the disks can freely separate as they are rotated. It will be realized that the relieving of the pressure which normally clamps the disks together is similarly effected when either a right-hand or a left-hand disk of a pair is reset.

In order to prevent the operator from accidentally turning the crank 414 in the wrong direction when it is desired to reset one of the disks 362, the illustrated machine includes mechanism actuated by the crank 408 which allows the crank 414 to be turned only in the proper direction, depending upon whether a right-hand or a left-hand disk 362 of a pair is to be reset. To this end, when the crank 408 is swung rearwardly preliminarily to the resetting of a right-hand disk 362, a link 470 (Fig. 14) pivoted at 472 to the segmental gear 398 is moved forwardly to move a pawl 474 into engagement with a ratchet wheel 476 fixed on the shaft 416, whereby counterclockwise movement of the shaft 416 is prevented. The pawl 474 is mounted on a lever 478 pivoted on a stud 480 fixed in one side of the yoke 418 and has pivoted to a downwardly extending arm substantially concentric with the marking disks 362 a block 482 having a bore adapted to receive the link 470. Movement of the link 470 is imparted to the lever 478 by springs 484 which are arranged to abut the opposite ends of the block 482 and are seated against washers 486 fixed to the link 470. It will now be apparent that, owing to the yielding connection between the link 470 and the lever 478, although the pawl 474 may be held against the ratchet wheel 476, the shaft 416 may nevertheless be rotated in a clockwise direction in or-

der to reset a right-hand marking disk 362. If, on the other hand, a left-hand marking disk is to be reset and the crank 408 is swung forwardly, the link 470 is moved rearwardly to cause a pawl 488 opposite to the pawl 474 to engage the ratchet wheel 476 and hence to prevent the shaft 416 from being turned except in a counterclockwise direction. It will also be understood that when the crank 408 is in its neutral position neither the pawl 474 nor the pawl 488 is in engagement with the ratchet wheel 476; but movement of the shaft 416 is prevented by the fact that the levers 378 positively hold the marking disks 362 against separation, which must occur if any is to be reset, by the engagement of the ends of the rods 394, 394 with the stop plates 388, 390.

In order to prevent the rotation during the resetting operation of all of the marking disks 362 except that to be reset, stop pawls 490 (Fig. 15), one for each pair of marking disks, are slidably mounted in the carrier 18 at the rear of the marking disks and have teeth 492 which are normally yieldingly held within a gap 432 between adjacent projections on each pair of marking disks by leaf springs 494 fixed to the carrier 18 and adapted to bear against the ends of the pawls 490. Mechanism will now be described by which that pawl 490 corresponding to a disk 362 to be reset is retracted from the disk to permit its rotation by one of the actuators 426. Each pawl 490 is grooved at 496 and a tooth 498 slightly narrower than the pawls and formed on the lower end of an arm 500 is adapted to enter the grooves 496 and to slide from pawl to pawl in the grooves 496 when in alignment with each other. The arm 500 is mounted on a shaft 502 (Fig. 17) which is rotatably and slidably mounted in the carrier 18 and is adapted to be moved axially so that the arm 500 always engages that stop pawl 490 which corresponds to the selected actuator 426 which is engaged by the tooth 446 on the shaft 438 at that time. To this end, a plate 504 is rotatably mounted on the shaft 502 between collars 506 fixed thereto and is provided with an arcuate slot 508 (Fig. 18) through which passes the left-hand end of the shaft 438. A collar 510 (Fig. 17) fixed to the shaft 438 is spaced from and cooperates with the hub of a crank 512 by which the shaft 502 is rotated to cause the plate 504 to move laterally to the same extent that the shaft 438 moves axially owing to its threaded connection with the bracket 436 when the tooth 446 is brought opposite to the actuator for a selected pair of disks. When the bracket 436 is swung as described above to move the selected actuator 426 into the gap 432, either before the yoke 418 is swung forwardly to reset the right-hand disk 362 or at the end of the forward movement of the yoke 418, as when a left-hand disk is to be reset, the shaft 438 is swung downwardly so that during the swinging movement of the yoke 418 either forwardly or rearwardly a tooth 514 (Fig. 18) on the shaft 438 engages the upper end of an arm 516 which, through connections to be described later, causes the locking pawl 490 corresponding to the marking disk being reset to be moved out of the path of the projections on this marking disk. The arm 516 is pivoted on an extension 518 of the bearing 420 (Fig. 15) on which the yoke 418 swings and carries pins 520 adapted to operate a link 522 when the arm 516 is swung in either direction, the link 522 being pivoted to an arm 524 extending downwardly from and fixed to the shaft 502. 75

At the end of the movement of the selected actuator 426 in either direction, which causes a resetting of the marking disks 362, as the bracket 436 swings upwardly carrying with it the shaft 438, the tooth 514 is removed from engagement with the arm 516, thereby permitting the retracted pawl 490 to be moved to its operative position under the influence of its spring 494. However, if for any reason the resetting movement of the 10 disk 362 is not completed and the pawl 490 is prevented from being returned to its locking position either by interference with a projection on the marking disk or by the continued engagement of the tooth 514 with the arm 516, safety mechanism 15 now to be described positively prevents the operator from treading the machine. This means comprises a locking lever 526 (Fig. 15) pivoted at 528 to the carrier 18 and which is engaged by the springs 494 behind the rear ends of all of the 20 pawls 490 and is swung rearwardly, when any pawl is retracted, into one of the other of two recesses 530, 532 formed in the plates 388, 390, respectively. Thus the lever 526, when held within one of the recesses 530, 532 by a retracted 25 pawl 490, prevents any rotation of the shaft 392 and hence movement of the crank 408 from the extreme position to which it will have been moved prior to a disk resetting operation. As explained above, movement of the crank 408 to 30 either of its extreme positions causes the rod 88 positively to prevent treading of the machine.

If the shaft 438 were to be rotated before the shaft 416 has been rotated through a complete revolution when the tooth 430 of the selected 35 actuator 426 has been moved into the gap 432 and one of the pawls 490 has been retracted, damage to the machine might result owing to the groove 496 in the retracted pawl being out of line with the grooves in the remaining pawls and to the 40 fact that the tooth 498 which is in the groove of the retracted pawl 490 would become jammed against the adjacent pawl.

In order to prevent rotation of the shaft 438 under these circumstances, the shaft 438 is arranged to be locked, in such a position that the tooth 446 is directed downwardly, by a pawl 534 (Fig. 20) pivoted on the shaft 428 and adapted to engage a notch 536 formed in the periphery of a collar 538 which is splined on the shaft 438. 50 Before the bracket 436 is swung toward the marking disks 362 to move the selected actuator 426 into the gap 432, the pawl 534 is yieldingly held in the notch 536 by a spring 540 one end of which abuts an arm 542 connected to the pawl 534 and 55 the other end of which is seated against a shoulder on the yoke 418. However, when the bracket 436 is swung to move the actuator 426 into the gap 432 the arm 542 is moved into engagement with the end of a stop screw 544 adjustably threaded in the yoke 418 whereby the pawl 534 is positively held within the recess 536 positively to prevent rotation of the shaft 438 during the setting of a marking disk.

In order to insure that the projections on the 65 marking disks 362 will be in alignment with each other laterally of the marking head after the resetting of one or more of the marking disks has been effected, the illustrated machine is provided with an alining arm 546 pivoted at 548 on the left-hand side of the carrier 18 and having a curved end 550 shaped to enter between the opposed inclined faces 551 of successive rows of projections 369 on the marking disks 362. The arm 546 is adapted to be held yieldingly against the marking disks 70 75 362 during the marking operation but is positively

retracted from the marking disks so as to allow them to be freely rotated during a resetting operation. The mechanism for thus operating the arm 546 includes a rod 552 (Figs. 1 and 7) pivoted at one end to the arm 546 and slidably mounted at its other end in a block 554 pivoted at 556 to one side of a forked lever 558 mounted at 560 to swing on the carrier 18. The lever 558 is operated from the shaft 402 by a toggle one arm 562 of which is fixed to the shaft 402, the other arm 564 being pivoted to the lever 558 at 566. As the toggle 562, 564 is broken in either direction as a result of moving the crank 408 from its neutral position preliminarily to setting one of the marking disks 362, the lever 558 is swung forwardly and causes 15 the block 554 to engage a shoulder 568 on the rod 552, whereby the arm 546 is positively withdrawn from the marking disks 362. When the crank 408 is again returned to its neutral position after the resetting of a marking disk has been completed, the toggle 562, 564 is straightened, thereby swinging the lever 558 rearwardly and causing the arm 546 to be yieldingly held against the marking disks 362 to align them laterally of the marking head through a spring 570 which 20 abuts the rear end of the block 554 and is held on the rod 552 by check nuts 572.

It is understood that by the use of the marking disks 362 alone the marking head 10 is adapted to impress two rows of marking characters simultaneously upon a work-piece. In some instances it is desirable to mark the work with three or more rows of characters simultaneously. To this end the illustrated machine comprises an auxiliary marking member 574 (Figs. 15 and 21) 35 having formed therein a recess with beveled sides 576 adapted to receive the projections 369 on the marking disks 362 so that the lower surface of the marking member 574 may be moved into the same plane as that of the characters on the marking head which extends through the member 574. The marking member 574 may have fixed thereto as many rows of marking characters as its size permits. The auxiliary marking member 574 has a slide 578 received in a guideway in a lever 580 (Figs. 15 and 17) which is pivoted at 582 to the carrier 18 so as to permit the marking member 574 to be swung away from the marking disks 362 when they are to be reset. Such control of the marking member 574 is effected by an eccentric 584 fixed to the shaft 392 against which the rear end of the lever 580 is held by a spring 586. It will now be apparent that when the crank 408 is moved to either of its extreme positions the eccentric 584 permits the spring 586 to swing the 45 lever 580 so as to move the marking member 574 out of the path of the projections on the marking disks 362. The marking member 574 is releasably locked in the lever 580 by means of a latch 588 (Figs. 15 and 21) on one end of a bell crank 590 50 pivoted at 592 to the lever 580.

In operating the machine, assuming that the disks have been set to print the proper legend and that the guard 98 has been moved down into its operative position, a piece of work will 55 be positioned on the work support in contact with the gages and the treadle depressed. This will cause the work support to be reciprocated, clamping the work by the bars 206 and carrying it into a position beneath the marking head 10. 70 The marking head 10 will then move down into contact with the work by reason of oscillation of the carrier 18. As the head rises, the work support will return to its forward position and the work piece will be released. During this 75

cycle of operation, the web 16 will be moved once before the impression is made and again, as the head is rising, before the completion of the cycle of the machine.

5 If the operator desires to reset the type disks, the guard will be raised and assuming that a right-hand disk of a pair is to be moved, the crank 408 will be moved away from the operator, thus allowing all disks to the left of the chosen 10 one to be moved laterally. The crank 512 will be rotated to turn the screw 438 and shift the tooth 446 into alignment with the actuator 426 which is associated with the chosen disk. If, then, the crank 414 is rotated clockwise, once for each 15 type space on the disk, the cam 422 will oscillate the yoke 418, carrying with it that actuator 426 which has been depressed and turning the corresponding disk a notch. During this time, the pressure on the disks will have been relieved by 20 the action of a cam 448 so that the disks can move to the left slightly while at the same time a sufficient spring pressure is maintained to keep them from separating at other than the desired point. At the end of half of the oscillation of 25 the yoke 418, the actuator 426 will be removed from the disks and the oscillation of the yoke 418 completed. This crank 414 can only turn in the proper direction because of the pawl 474 and the ratchet 476. All other disks except the 30 one to be reset are held by the stop pawls 490. That pawl which normally prevents rotation of the disk being reset is removed therefrom by the arm 500 during this resetting operation and is returned into engagement with the disk at the 35 end of the resetting cycle. If the pawl is not completely returned, then the lever 526 (Fig. 15) will prevent the crank 408 from being restored to its normal depending position. If the resetting has been properly completed, however, 40 this crank will be brought back to its normal position and the disks will be aligned by the curved end 550 (Fig. 2) of the lever 546.

It is impossible to treadle the machine while the guard is up and if the treadle is being held down as the guard is depressed, then it will 45 have to be retreadled before the clutch is thrown in. Furthermore, the machine cannot be treadled while the disks are being reset because the link 410 operates to lock the treadle whenever the crank 408 is swung out of its normal 50 depending position.

Having thus described our invention, what we claim as new and desire to secure by Letters Patent of the United States is:

55 1. In a marking machine, a plurality of marking disks mounted for rotative and axial movement, means for selectively rotating said disks to reset them, means for yieldingly holding said disks together against axial movement, and means for relieving the yielding pressure between the disks when one is reset.

60 2. In a marking machine, a plurality of marking disks mounted for rotative and axial movement, means for selectively rotating said disks to reset them, means for yieldingly holding said disks together against axial movement, and mechanism operated by said first-mentioned means for relieving the yielding pressure between the disks when one is reset.

65 70 3. In a marking machine, a plurality of rotatively mounted marking disks, means for resetting the disks comprising an actuator mounted for movement into engagement with a selected disk and peripherally thereof to rotate it, means for yieldingly holding said disks

75 together against axial movement, and means actuated by movement of said actuator into engagement with said disk for relieving said yielding pressure.

4. In a marking machine, a plurality of rotatable marking disks, means for resetting said disks mounted for movement successively into engagement with a selected disk and peripherally thereof to rotate it, means for yieldingly holding said disks together against axial movement, connections between said disks for displacing from the disk being reset the remaining disks at one side thereof, and means operated progressively as said remaining disks are displaced for relieving the axial pressure between the disks 15 throughout the resetting of the selected disk.

5. In a marking machine, a marking head comprising a plurality of marking disks mounted for rotative and axial movement, resetting means for selectively rotating said disks to reset them, 20 members mounted to swing laterally of said head for controlling the axial movement of said disks, yielding means normally acting upon said members to cause said disks to be yieldingly held together, a cam lever associated with said yielding means, and connections between said resetting means and said cam lever for causing said yielding means to be compressed when a disk is reset whereby the pressure between said disks is relieved.

6. In a marking machine, a plurality of marking disks mounted for rotative and axial movement, disk resetting means for selectively rotating said disks, said disks having means thereon rendered operative by rotation of the disk being 35 reset to displace the remaining disks at one side thereof axially, members for controlling the axial movement of said disks constructed and arranged normally to hold said disks yieldingly together, and connections between said resetting 40 means and members for moving that member adjacent to the displaced disks to the same extent that the displaced disks are moved axially.

7. In a marking machine, a marking head comprising a plurality of marking disks mounted for rotative and axial movement, disk resetting means movable successively into engagement with a disk to be reset and peripherally thereof to rotate it, said disks having means thereon for displacing from that disk being reset the remaining disks at one side thereof, members disposed at each side of said head for controlling axial movement of said disks, yielding means for causing said members to exert a yielding pressure on the disks, and means for relieving the 55 pressure of said yielding means and progressively limiting the displacement of that member adjacent to the displaced marking disks whereby the disks are held in contact with each other although the yielding pressure between them has 60 been relieved.

8. In a marking machine, a marking head comprising a plurality of marking disks mounted for rotative and axial movement, disk resetting means movable successively into engagement 65 with a disk to be reset and peripherally thereof to rotate it, said disks having means thereon for displacing from the disk being reset the remaining disks at one side thereof, members disposed at the sides of said marking head for controlling the axial movement of said disks, and connections operated by said resetting means for progressively moving that member adjacent to said remaining disks away from said head as said 70 remaining disks are displaced.

9. In a marking machine, a plurality of marking disks mounted for rotative and axial movement, means for selectively rotating said disks to reset them, means for normally locking said disks against axial movement comprising members movable to permit axial movement of the disks at one side of that being reset, treadle-operated means for initiating a marking operation, and stop means actuated by said locking means for preventing the operation of said treadle means when said locking means is moved to permit axial movement of said disks.
10. In a marking machine, a marking head comprising a plurality of marking disks mounted for rotative and axial movement, means for selectively rotating said disks to reset them, means for normally locking said disks against axial movement comprising members movable individually to permit axial movement of the disks at one side of that being reset, treadle-operated means for initiating a marking operation, a guard mounted for movement away from said head to permit access thereto, and stop means actuated by said guard or said locking means for preventing the operation of said treadle-operated means.
11. In a marking machine, a plurality of marking disks mounted for rotative and axial movement, retractible locking pawls for said disks, means for selectively rotating said disks to reset them, means for normally locking said disks against axial movement comprising a manually operable control member, treadle-operated means for initiating the marking operation, means interposed between said locking pawls and said control member for preventing the return of the control member to a normal position when a pawl is out of locking position, and means between the control member and the treadle-operated means for preventing the operation of the treadle means when said control member is out of normal position.
12. In a marking machine, a plurality of marking disks mounted for rotative and axial movement, means for locking said disks against axial movement comprising a control member adapted to be moved toward either side of a neutral position in which said disks are locked by said means against any axial movement, means for selectively rotating said disks to reset them, members for locking said disks against rotative move-
ment, means for retracting that locking member associated with the disk being reset, and means cooperating with said locking members to prevent the movement of said control member into its neutral position while any locking member is in retracted position.
13. In a marking machine, a plurality of marking disks, means for selectively rotating said disks to reset them, members for locking said disks against rotative movement, means for retracting that locking member associated with the disk to be reset, a control member, treadle-operated means for initiating a marking operation, means operated by movement of said control member for rendering said treadle means inoperative, and connections between said locking members and said control member constructed and arranged to prevent the control member from being moved to render said treadle means operative when any locking member is retracted.
14. In a marking machine, a plurality of marking disks mounted for rotative and axial movement, means for selectively rotating said disks to reset them, pawls arranged normally to prevent said disks from rotating, means for retracting that pawl associated with the disk being reset, means for locking said disks against axial movement comprising rotatable plates, a control member for rotating said plates to permit axial movement of said disks in one direction, and connections between said pawls and said plates arranged to lock said control member against movement whenever a pawl is retracted.
15. In a marking machine, a plurality of marking disks mounted for rotative and axial movement, pawls mounted and arranged normally to prevent rotative movement of said disks, means for retracting that pawl associated with a disk to be reset, means for selectively rotating said disks to reset them, means for locking said disks against axial movement in one direction during the resetting of a disk comprising a plate having a recess, a control member for operating said plate, and a member adapted to be moved into the recess in said plate by the retraction of any pawl to prevent said control member from being moved while any pawl is retracted.
